GRAVITY OPERATED LOCKING MEANS FOR
CHAIR CASTERSAage Adelsten Eriksen, Oslo, Norway, assignor to
Arne Syversen, Oslo, NorwayApplication July 22, 1947, Serial No. 762,763
In Norway July 23, 1945

1 Claim. (Cl. 16—33)

1

The present invention relates to a device for use on furniture, especially chairs, in order to enable the same to be easily moved on the floor. The ordinary casters which frequently for this purpose are mounted on the legs or feet of the furniture have the disadvantage that the floor easily is injured due to the small area of engagement between the casters and the floor. It has therefore for furniture been proposed different devices comprising casters or wheels which normally without load engage the floor surface, but which are adapted to be lowered relative to the furniture and locked in the lowered position, so that the furniture may be rolled on the wheels. The present invention has for its object an especially simple construction of a device of this kind, by means of which it is obtained that the wheels by tilting the chair automatically are lowered and locked in the lowered position, as also the wheels may be released from the locked position by tilting the chair.

With this object in view and according to the invention the wheels are mounted each one on a bolt or stem which is vertically slidable in a fitting attached to the lower side of the chair preferably to the frame of same, the said bolt or stem being, by tilting of the chair, adapted through the force of gravity to be automatically lowered, and locked in the lowered position by means of members which also through the force of gravity enter into locking engagement with each other.

According to one embodiment the said bolt or stem is adapted to be locked in the lowered position by means of a lever or pawl which is swingable through the force of gravity.

According to another embodiment the said bolt or stem is swingably mounted and adapted by lowering and swinging of the same to be caused to enter into locking engagement with a stationary mounted locking member.

The invention is illustrated in the drawing, in which:

Fig. 1 shows a chair provided with a device according to the invention.

Fig. 2 is a side view partly in section of an embodiment of the device according to the invention.

Fig. 3 is a side view partly in section of another

embodiment of the device according to the invention.

In Fig. 1, 1 designates a chair on each side of which to the frame 2 of same, fittings 3 are attached for the mounting of the wheels 4.

In the embodiment shown in Fig. 2 of the device according to the invention, the wheel 4 is mounted on a bolt 5 which is slidable in the sleeve 6, which preferably is integral with the fitting 3. The wheels are normally held in their upper position on account of their engagement with the floor surface without being subjected to any load from the chair. To the fitting is further swingably attached a locking lever or pawl 7 with a locking tooth 8, which when the chair is tilted rearwardly and the bolt 5 falls down, automatically falls into a notch 9 in the bolt 5 and locks the latter. In this way the chair may, while resting on the wheels, be rolled to the desired place. When here the wheels are to be set back into normal position in order that the chair shall rest on the legs, one may only tilt the chair forwardly, whereby the pawl 7 by the force of gravity will fall out of engagement with the notch 9, and when then the chair is rapidly moved back, the wheels and the bolt 5 will be pressed back into normal position resting against the floor surface.

In the embodiment shown in Fig. 3, 10 designates a fitting intended to be attached to the inside of the frame of the chair. In the fitting is on a bolt 11 swingably suspended a stem 12 which at its lower end carries the wheel 4. The stem is provided with a slot 13 through which the bolt 11 passes, so that the stem may as well swing about the bolt 11 as be slid up and down, the bolt being guided in the slot 13.

The stem 12 has further a notch 14, which when the chair is tilted rearwardly and the stem falls down and swings by the force of gravity, falls into locking engagement with a pin 15 secured in the fitting; the stem may again be released from the locking engagement by tilting the chair forwardly.

45 I claim:

A caster for chairs and the like comprising a fitting member adapted for fastening to the frame of a said chair, a bolt in said fitting, an elongated caster stem having a longitudinal slot therein pivoted on said bolt and being slidable

thereon with respect to said fitting member, a wheel rotatably journaled on the lower end of said stem, a pin secured in said fitting, said stem having a notch in a side thereof for coaction with said pin, said pin and said notch comprising means to lock said stem in a predetermined relationship with said fitting, said locking means operating automatically by the force of gravity when the chair is tilted in one direction to lock and when tilted in an opposite direction to unlock said stem and said pin.
